UNITED STATES PATENT OFFICE.

MARTIN J. DONER, OF CHICAGO, ILLINOIS, ASSIGNOR, BY DIRECT AND MESNE ASSIGNMENTS, TO INVENTORS SPECIALTY MANUFACTURING COMPANY, OF CHICAGO, ILLINOIS, A CORPORATION OF ILLINOIS.

SHEET-METAL STRUCTURE.

1,161,764.

Specification of Letters Patent. Patented Nov. 23, 1915.

Application filed October 24, 1911. Serial No. 656,459,

To all whom it may concern:

Be it known that I, MARTIN J. DONER, a citizen of the United States, residing at Chicago, in the county of Cook and State of Illinois, have invented a new and useful Improvement in Sheet-Metal Structures, of which the following is a specification.

My invention relates to sheet-metal structures for use more particularly in constructing partitions and other wall-structures which are not required to support any appreciable weight and ceilings, of plaster-board, tile, or the like material, for securing the latter in place; and my object, generally stated, is to provide a construction of sheet-metal strip for the purposes stated which may be economically and easily manufactured, which shall involve in its manufacture the minimum amount of metal commensurate with the strength required, and which will permit the plaster-binder used at the joints of the board or tile and at which the sheet-metal strips lie, to interlock with said strips and unite with the boards or tile to form a homogeneous mass united with and connecting together adjacent boards or tiles.

Referring to the accompanying drawings—Figure 1 is a broken perspective view of an angular shaped single partition of plaster-board or tile joined together at the corner of the partition and at their alining sections with metal strips, in the form of studding, constructed in accordance with my invention. Fig. 2 is a plan view of the structure shown in Fig. 1 with the plaster-finish omitted. Fig. 3 is a broken perspective view of the studding shown in Fig. 1 for connecting plaster-boards or tile together in alining condition. Fig. 4 is a similar view of the studding shown in Fig. 1 for securing the plaster-boards or tile at the corner of the partition. Fig. 5 is a broken perspective view of a double plaster-board or tile partition, the sections of which are secured together by studding constructed in accordance with my invention. Fig. 6 is a plan view of a double plaster-board or tile partition having an offset-portion, the sections of which are secured together by studding constructed in accordance with my invention; and Fig. 7 is a horizontal section taken through a double wall showing a

furring strip, constructed in accordance with my invention, for holding the inner wall in spaced relation to the outer wall.

Referring particularly to the construction illustrated in Figs. 1 to 4 inclusive, in which a single wall plaster-board or tile partition is illustrated, the sheet-metal studding for securing the plaster-boards or tile in alining condition between the ends of straight sections of the partition, are shown at 7 and the studding for the corners at which the sides of the partition meet when an angular partition is to be constructed, are shown at 8. Each length of studding 7 is formed of a single sheet of steel, or other suitable sheet-metal, from the longitudinal edge-portions of which are cut perforated tongues 9 which reach short of the extreme outer longitudinal edges of the studding as represented, whereby sections 10 connected with the body-portion of the studding by webs 11, are provided at opposite sides of the studding. It is preferred that the metal forming the body-portion of the studding be bent at its longitudinal central portion into substantially U-shaped form as represented at 12, or into V-shape and preferably 70 perforated as represented at 12^a, whereby a channel 13 is formed in the studding, and its tongues 9 bent to extend at angles to the portion 12 and project laterally in opposite directions as represented in Figs. 1 and 2, 85 the webs 11 being bent, at angles to the tongues 9, preferably at their bases and bent intermediate their ends, as represented at 14, to cause the sections 10 to extend substantially parallel with the adjacent series 90 of tongues 9, and form therewith oppositely opening channels 15 which extend longitudinally of the studding and into which the plaster-boards or tile extend, as hereinafter described.

The studding 8 is of the same construction as the studding 7 except that the body-portion of the studding 8 is bent to cause the parts of the studding forming the channels 15 to extend at the desired angle to each other for securing the boards or tile, as hereinafter described, in the desired angular relation at the corner of the partition. In the studding 8 the body-portion thereof is of V-shape, as represented at 16, to form a 100 bead-edge 17 and a channel 18, the walls of

the portion 16 being perforated, as represented at 19, for a purpose hereinafter described.

In practice, assuming that an angle partition is to be constructed, the studding 7 and 8 are secured to the ceiling and floor of the room to be partitioned, as by nailing them thereto at lugs 20 provided on opposite ends of the studding, as represented at the lower 10 end of the studding 7 in Fig. 3, the studding being positioned at distances apart slightly greater than the width of the plaster-boards or tile to be used for the main-portion of the partition. For the straight sections of 15 the partition the studding 7 is employed, and for the corners thereof where the straight partition-sections meet the studding 8 is used. After the studding is positioned as described, the plaster-boards or tile, such 20 as that represented at 21, are inserted into the opposing channels 15 of the studding, and for the purpose of permitting these boards or sections of tile to be readily positioned in the channels 15, I provide the 25 walls forming the channels 15, of studding of sufficient width to permit each board or section of tile to be inserted at one edge into an adjacent channel 15, then swung to bring its opposite edge into alinement with its 30 adjacent channel 15 and the boards or sections thereupon moved lengthwise to cause the boards or sections to extend at their opposite edges into adjacent channels 15, thus permitting the studding to be erected before 35 the boards or sections of tile are inserted into place therein.

After the boards or tile 21 have been assembled with the studding as described, the opposite surfaces of the partition so 40 formed are covered, as is usual, with a coating of plaster which is indicated at 22 and, as represented in Fig. 1, covers the boards or tile 21 and fills the spaces between the sections of the studding, entering the cut- 45 away portions 23 between the webs 11, the perforations 12^a and 19, the spaces between the tongues 9 and the other recessed portions of the studding. The plaster also enters into the spaces between the inner walls 50 of the channels 15 and those edges of the boards or tile 21, which in adjusting the boards or tile to position as described, preferably reach short of the inner walls of the channels 15. The coating of plaster thus 55 applied to the partition, by engaging with the sections of the latter as stated, is thus securely anchored to the partition and firmly held in place and forms a homogeneous section of plaster extending from one board 60 21 to the other.

Referring to the construction illustrated in Figs. 5 and 6 in which I show a double-walled partition employing studding constructed in accordance with my invention, 65 the studding for alining sections of the par-

tition are represented at 24 and the studding suitable for the corners of the partitions are shown at 25 and 25^a. In a partition of this character the walls thereof are arranged in spaced relation affording an 70 air-space between them, and to this end the studding 24 is each formed of a central Z-shaped section 24^a the lateral edge-portions of these studding being reversely bent to afford oppositely-opening relatively deep 75 channels 26 and 27, the distance between which determines the width of the space between the walls forming the double partition. To provide channels for receiving the edges of the boards or tile which are to be secured in alinement with the boards or tile entering the channels 26 and 27, I cut from the metal of the portions of the studding forming the rear and outside walls of the channels 26 and 27, tongues 28 and 29, 80 these tongues being perforated and arranged in staggered relation, as represented in Fig. 5 and being bent to extend substantially parallel with relation to each other and with 85 relation to the walls of the channels 26 and 27. It will be noted that by providing the tongues as stated, they in effect form channels, which by preference are relatively shallow, having skeleton walls, for receiving the lateral edges of plaster-boards or tile, as 90 hereinafter described. The studding 25 and 25^a are of forms suitable for the joining of the plaster-boards or tile at the corners of the partition, the studding 25 being of the same construction as the studding 8, excepting that the body-portions thereof represented at 30 are somewhat wider than the body-portions of the studding 8, to cause 95 bead-portions 31 to lie at the outer surface of the plaster-coating, as hereinafter described. The studding 25^a is the same as studding 8 excepting that their body-portions are formed of wider strips of metal 100 and bent as illustrated in Fig. 6 to form a bead 32 which is strongly braced against 105 bending and extends to the outer surface of the plaster-coating, as hereinafter described.

In practice, the studding 24, 25 and 25^a would be secured to the floor and ceiling of the room to be partitioned, as described of the studding of Figs. 1 to 4 inclusive. The plaster-boards or tile 21 would then be inserted into the channels 26 and 27 and into the channels formed by the tongues 28 and 29, the relatively deep walls of the channels 26 and 27 permitting of the insertion of the boards 21 into engagement with the walls of the channels of the studding adjacent to the opposite edges thereof, as described of the construction in Figs. 1 to 4 115 inclusive. The plaster coating represented at 33 is then applied to the outer surfaces of the partition thus provided, the plaster entering the recessed portions of the walls of the channels 26 and 27, the spaces between 120

the tongues 29 and the openings therein, and between the end-walls of the channels 26 and 27 in the studding and those ends of the boards or tile 21 which reach short of such end-walls, whereby the plaster-coating 33 is firmly anchored to the partition, and produces a homogeneous plaster binder as described of the preceding construction.

10 The beadings 31, 32 and 17 are preferably so disposed relative to the other parts of the strips that they will lie at the exposed surfaces of the plaster-coatings 33 and 22, respectively, and thus form means for protecting the corners of the partitions.

15 Referring to the construction illustrated in Fig. 7, a wall, such as an outside brick-wall, is represented at 34 and an inner wall spaced therefrom at 35, the latter being secured in spaced relation to the wall 34 by 20 means of furring strips 37, one only of which is shown, and which connect the plaster-boards or tile at their adjacent upright edges as represented. The furring strips 37 are of the same construction as the studding 25 of Fig. 5, except that the grooves at one side thereof are omitted and that portion of the strip which is indicated at X and is connected with the web 24^a serves to seat against the wall 34 and be secured thereto as represented at 38. It will be manifest that strips 30 of this character, or similar thereto, may be used in the constructing of a plaster-board or tile ceiling by securing the strips at their sections X and inserting the plaster-boards 35 or tile, to form the ceiling, into the grooves 26 and 27, the latter in this case extending substantially parallel with the ceiling. Further, my improved metal strips may be used in constructing walls about columns and 40 other structures.

It will be noted that by constructing metal strips in accordance with my invention, they may be readily formed from single sheets of metal by stamping them to form, whereby 45 they may be easily and economically manufactured.

What I claim as new, and desire to secure by Letters Patent, is—

1. A sheet-metal stud, for the purpose set forth, having a longitudinally-extending body-portion provided along an edge with wings forming a channel for receiving a board, or section of tile, the base and one wall of said channel being formed of angle-shaped members connected with said body-portion adjacent to the points at which the other wall of said channel is connected with said body-portion, the base of said channel extending at an angle to the walls thereof 55 and the portions of said angle-members which form the base of said channel being spaced apart and spaced from said body-portion.

2. A sheet-metal stud, for the purpose set forth, having a longitudinally-extending

body-portion provided along an edge with wings forming a channel for receiving a board, or section of tile, the base and one wall of said channel being formed of angle-shaped members connected with said body-portion adjacent to an edge of the latter and the other wall of said channel being formed of tongues cut from between said angle-members and connected with said body-portion adjacent to the points of connection of said angle-members with the latter, the base of said channel extending at an angle to the walls thereof and the portions of said angle-members which form the base of said channel being spaced apart and spaced from said body-portion. 70

3. A sheet-metal stud, for the purpose set forth, having a longitudinally-extending channelled body-portion provided along an edge with wings forming another channel for receiving a board, or section of tile, the base and one wall of said board-receiving channel being formed of angle-shaped members connected with said body-portion adjacent to the points at which the other wall of said channel is connected with said body-portion, the base of said channel extending at an angle to the walls thereof and the portions of said angle-members which form the base of said channel being spaced apart and 80

90

95

4. A sheet-metal stud, for the purpose set forth, having a longitudinally-extending body-portion provided along opposite edges with wings forming channels for receiving boards, or sections of tile, the base and one wall of each channel being formed of angle-shaped members connected with said body-portion adjacent to the points at which the other wall of the channel is connected with said body-portion, the base of said channel extending at an angle to the walls thereof and the portions of said angle-members which form the bases of said channels being spaced apart and spaced from said body-portion. 100

105

110

5. A sheet-metal stud, for the purpose set forth, having a longitudinally-extending body-portion provided along opposite edges with wings forming channels for receiving boards, or sections of tile, the base and one wall of each channel being formed of angle-shaped members connected with said body-portion adjacent to an edge of the latter, and the other wall of the channel being formed of tongues cut from between said angle-members and connected with said body-portion adjacent to the points of connection of said angle-members with the latter, the base of said channel extending at an angle to the walls thereof and the portions of said angle-members which form the bases of said channels being spaced apart and spaced from said body-portion. 115

120

125

6. A sheet-metal stud, for the purpose set 130

- forth, having a longitudinally-extending channelled body-portion provided along opposite edges with wings forming other channels for receiving boards, or sections of tile, 5 the base and one wall of each board-receiving channel being formed of angle-shaped members connected with said body-portion adjacent to the points at which the other wall of the channel is connected with said 10 body-portion, the base of said channel extending at an angle to the walls thereof and the portions of said angle-members which form the base of said channel being spaced apart and spaced from said body-portion.
- 15 7. A sheet-metal studding, for the purpose set forth, comprising a longitudinally extending body-portion provided at its opposite longitudinal edges with pairs of wings, the members of each pair being substantially 20 parallel and forming the side walls of alining channels extending in opposite directions for receiving boards, or sections of tile, said body-portion being of a width transverse to said channels substantially equal to 25 the width of said channels, with the opposite edges of said body-portion extending substantially flush with the side walls respectively of said wings.
8. A sheet-metal studding, for the purpose 30 set forth, comprising a channelled longitudinally extending body-portion provided at its opposite longitudinal edges with pairs of wings, the members of each pair being substantially parallel and forming the side 35 walls of alining channels extending in opposite directions for receiving boards, or sections of tile, said body-portion being of a width transverse to said channels substantially equal to the width of said channels, 40 with the opposite edges of said body-portion
- extending substantially flush with the side walls respectively of said wings.
9. A sheet-metal studding, for the purpose set forth, formed of a body-portion provided with channels directly opposing, and 4 in line with, each other, said channels being located at opposite longitudinal edges of said body-portion and directly opposing and in line with the latter and extending in opposite directions wholly beyond said body-portion for receiving boards, or sections of tile, each of said channels having a base-portion and side walls, said base-portion and side walls being formed of sections separate from said body-portion and secured to and 5 extending beyond the latter, whereby the walls and bases of said channels form no part of said body-portion.
10. A sheet-metal studding, for the purpose set forth, formed of a channelled body-portion provided with channels directly opposing, and in line with, each other, said channels being located at opposite longitudinal edges of said body-portion and directly opposing and in line with the latter 65 and extending in opposite directions wholly beyond said body-portion for receiving boards, or sections of tile, each of said channels having a base-portion and side walls, said base-portion and side walls being 70 formed of sections separate from said body-portion and secured to and extending beyond the latter, whereby the walls and bases of said channels form no part of said body-portion.

MARTIN J. DONER.
